Edward Mayer

United States Patent Office.

EDWARD MAYER, OF PHILADELPHIA, PENNSYLVANIA.

Letters Patent No. 64,780, dated May 14, 1867.

IMPROVEMENTS IN BOOTS AND SHOES.

The Schedule referred to in these Letters Patent and making part of the same.

TO ALL WHOM IT MAY CONCERN:

Be it known that I, EDWARD MAYER, of the city of Philadelphia, in the State of Pennsylvania, have invented a new and useful Improvement in Boots and Shoes; and I do hereby declare that the following is a full and exact description of the same, reference being had to the accompanying drawings, making a part of this specification, in which—

Figure 1 is a side view of a boot having my improvement applied thereto; and

Figure 2, a transverse section of the same on the dotted line *x y* of fig. 1; like letters of reference indicating the same parts when in both figures.

The object of my improvement is to effectually preclude the entrance of water between the "upper" and the "sole," or between the "upper" and the "welt" of a boot or shoe, and my invention consists, substantially as hereinabove described and set forth, in making and applying the "insole" of a boot or shoe so that its edges shall extend upward around the inside of the front and two sides of a boot or shoe, sufficiently high to preclude the entrance of water into the boot or shoe through the joint formed betweeen the "upper" and the "welt," and also, in the application of a narrow band of leather, or its equivalent material, around between the outside sole and the "upper," at the sides and front or toe of a boot or shoe, so as to prevent the entrance of water between them.

In the drawings, A is the upper; B the outside sole; C the insole; D the usual slip-sole; E the welt, and F the band. The insole C is cut in one piece, and of such a form as will cause it to extend upward a little above the dotted line *a'* of the forward half of the boot or shoe, (see fig. 1). It is then wetted and applied to the last, its extreme upper edges being chamfered off thin, as shown in fig. 2. The "upper" A is then applied over the last and "insole" in the usual manner. I now prepare the welt E and sew it fast to the upper A and insole C in the usual manner, and then apply the usual slip-sole D and the outside sole B, and shape their edges in the manner usual, and preparatory to sewing them together. I now prepare the narrow band F, apply it as represented in the drawings, and sew it and the welt E, with the sole B, by a single line of stitches, in the usual manner. I now withdraw the last and then secure the thin upper edge of the insole C to the upper A by stitching through both from outside to inside, and from inside to outside alternately, as indicated by the dotted line *a'* in fig. 1, and finally I then in like manner stitch the upper edge of the band F fast to the "upper" A and "insole" C, as indicated by the dotted line *b'* in fig. 1. (See also fig. 2.) It will therefore be readily seen that it will be impossible for water to reach the foot of the wearer by leaking into the boot or shoe between the "upper" and the "welt," because the raised edges of the insole C will be a perfect defence, and that the band F will be an additional defence, because it covers closely the usual joint between the edge of the outside sole and the "upper."

Having thus fully described my improvement, what I claim as my invention, and desire to secure by Letters Patent, is confined to the following, viz:

1. I claim extending the side and front edges of the "insole" of a boot or shoe upward around the inner side of the "upper," substantially as and for the purpose described.

2. I also claim the application of the band F over the joint formed between and by the "upper" and the "outside sole" of a boot or shoe, substantially as and for the purpose described.

EDWARD MAYER.
